DEVICE FOR MAKING BENT BRISTLE BRUSHES

William H. Howe, Bronxville, and Harold W. Reed, Brooklyn, N. Y., assignors, by mesne assignments, to Harry G. Liese, New York, N. Y.

Original application January 15, 1948, Serial No. 2,538, now Patent No. 2,621,080, dated December 9, 1952. 10 Divided and this application May 3, 1952, Serial No. 285,938

4 Claims. (Cl. 18—36)

This application is a division of application Serial No. 2,538 filed January 15, 1948, now Patent No. 2,621,080 granted December 9, 1952.

Our invention relates to the manufacture of brushes of the "bent bristle" type in which bristles have ends so bent toward the tip of the brush that the bristles converge and form a tapering tuft.

It is well known in the painting art that bent bristle brushes have advantages which ordinary brushes do not have. But, hitherto, the manufacture of bent bristle brushes has been cumbersome and expensive. Objects of our invention are to facilitate the manufacture of bent bristle brushes, to produce brushes with accurately bent and positioned bristles, and to reduce the cost of this production.

Other objects are a method for producing a brush having a tuft consisting of properly bent and arranged bristles, to avoid dislocation of the properly arranged bristles and to secure the properly bent shape of the bristles permanently.

Further objects are to provide a device facilitating the use of the inventive method, to provide a device adapted to hold ferrules and tufts during the bristle-bending operation in proper positions, and to provide a device allowing the simultaneous production of a large number of bent bristle brushes.

Still further objects are to provide this device with a structure that is easy to make, easy to handle and easy to maintain in good working condition, to make this device stiff and strong by providing the same with a frame of strong metal, to avoid direct contact of this metal frame with the bristles, and, thereby, to protect the bristles from scorching or corroding when the device is heated.

Still other objects and advantages will appear from the following description of an exemplifying embodiment of our invention, from the appended claims and from the accompanying drawing in which:

Fig. 1 shows a top view of a device adapted for the production of bent bristle brushes according to our invention, some top parts of this device being partly broken off, two ferrules provided with tufts being inserted in this device for the purpose of being treated according to our invention.

Fig. 2 shows a cross-section taken along the broken line 2—2 in Fig. 1, a screw bolt crossed by this line being represented non-sectionally.

Fig. 3 shows a cross-section taken along the line 3—3 in Fig. 1, a screw, a pin and a ferrule being represented non-sectionally.

Fig. 4 shows a top view of a ferrule provided with a bristle tuft before insertion and treatment according to our invention.

Referring to Figs. 1 to 3, numeral 1 indicates a flat strip or slat provided with a row of recesses 4. These recesses extend from the front of the strip 1 parallel to each other and have curved ends of that shape which the tufts of the produced brushes shall have. The drawing shows, for example, a strip 1 with six recesses 4. But any other desired number of recesses may be arranged in a strip of a length corresponding to this number.

Another strip 5 is affixed to the lower side of the strip 1 and closes the bottoms of the recesses 4. The strips 1 and 5 together form a unified body which constitutes

2

the concave part of a mould. This body is positioned in a metal frame comprising a strip or ledge 6 supporting the strip 5 and two blocks or walls 7 positioned adjacently to the ends of the strips 1 and 5. The strips 1 and 5 may be secured to each other by screws 8 and 9, some of which may additionally serve to affix the concave mould body to the frame or to its ledge 6. For example, the screws 9 extend from the strip 1 through the strip 5 into the ledge 6.

The frame is supported and re-inforced by angular rails 11 and 12 affixed to the lower side of the ledge 6. There may be two lateral rails 11 symmetrically positioned under the ends of the ledge 6, and a rail 12 running in the longitudinal direction of the ledge 6. The rails 11 and 12 form the feet of the frame and of the entire device.

Blocks or cover bodies 13 are affixed, for example, cemented to a common strip or ledge 14 and fit the recesses 4. One block 13 is provided for each recess 4. 20 When the ledge 14 contacts the top of the strip 1 as shown in the drawing, the blocks 13 reach into the recesses 4 a little less far than the bottoms of these recesses whereby spaces 15 with the open front sides are left in the recesses. These narrow spaces are adapted to hold bristle tufts confined in bent condition. The blocks 13 extend from the curved rear sides of the recesses 4 to the front not quite as far as the strip 5 whereby narrow front margins 16 of the strip 5's upper surface are left uncovered.

30 The blocks 13 and the ledge 14 together form a unified body constituting a convex mould part which fittingly co-operates with the concave mould part described before. This convex mould part may be reinforced by a rail 17 of angular cross-section. The rail 17 is positioned on top of the ledge 14 and runs in the longitudinal direction of the latter. The correct positions of the blocks 13 may be secured by pins 18 passing through bores in the rail 17, in the ledge 14 and in the blocks 13. The rail 17 may be affixed to the ledge 14 and to the blocks 13 in suitable manner, for example, by screws 19.

35 The rail 17 and, thereby, the convex mould part can be secured to the frame and to the other mould part by bolts 21 having screw threads engaging corresponding threads of bores in the frame blocks 7, and having heads 22 contacting washers 23 placed on the top surface of the rail 17. After removal of the bolts 21, the rail 17 can be taken off the blocks 7 whereby the convex and the concave mould parts are separated.

40 Another rail 24 of angular cross-section is affixed on top of the front ends of the rails 11 and forms a bridge from one rail 11 to the other. The rail 24 is positioned at a distance in front of the spaces 15 and has an edge 25 running parallel to the strip 5 and rising a little higher than this strip. The distance between the edge 25 and the strip 5 is a little shorter than the ferrules which will be described later.

45 Bent bristle brushes have been previously made by arranging bent bristles in proper positions and, then, affixing the thus arranged bristles to a ferrule or to a handle. The proper arrangement of the bristles is very difficult and cumbersome and is apt to be disturbed when the bristles are being affixed to the ferrule. According to our invention, natural animal bristles, for example, 50 pig bristles are bent after they are affixed to a ferrule. This method starts with brushes 26 of the type shown in Fig. 4. A brush of this type comprises a ferrule 27 to which a tuft 28 of ordinary or straight bristles is affixed. Such brushes are easy to make by well known methods and are available at low cost.

55 Further according to our invention, the tuft 28 is forced into the desired curved shape in which bristles are bent toward the tip of the tuft. While held in this shape, the tuft together with its ferrule is treated with hot, preferably boiling water for considerable time, for example, for two hours and a half. Then the tuft is dried while still held in the mentioned shape and while remaining affixed to the ferrule. The drying may take 60 place, for example, in a dryer of ordinary and well known structure, and may last for about four hours.

We have found that the boiling and subsequent drying treatment removes all tendency from the bristles to return to their original shape or to abandon the enforced bent shape. After this treatment, the enforcement of this shape is no longer necessary and the brush may be finished in usual and well known manner, the ferrule being affixed to a handle of any well known type.

The described method is facilitated, and its results are improved by the use of the device shown in Figs. 1 to 3. This device is used in the following manner:

One or, preferably, several brushes of the type shown in Fig. 4 are placed in the device while the upper part of the device comprising the top rail 17, the ledge 14 and the blocks 13 are removed. The drawing shows only two brushes inserted in the device. But there may be as many brushes inserted as there are recesses 4. Each of these brushes is so positioned that the tuft lies in a recess 4 and extends into the area over the margin 16 and that the ferrule 27 rests with its tuft-bearing end on this margin while the opposite end of the ferrule contacts the rail 24 or the edge 25 thereof.

Then, the temporarily removed parts of the device are affixed again to the remaining parts by means of the screw bolts 21. Hereby the concave and convex mould parts engage each other, the blocks 13 entering the recesses 4. When the bolts 21 are tightened, the blocks 13 are in their lowermost positions. The tufts are almost completely confined in the spaces 15 and are forced to assume the shape shown in Fig. 1 at 29. Only very short parts 31 of the bristles emerge from this space and project beyond the blocks 13.

Then, the entire device with the inserted brushes is immersed in water, and the water is kept at boiling temperature for about two hours and a half. The hot water contacts the parts 31 of the bristles and therefrom penetrates the entire tufts positioned in the moulding spaces 15.

Then, the entire device with the inserted brushes is placed into a drying chamber where it is kept as long as necessary for the removal of the moisture from the device and from the bristle tufts, that is, for about four hours. During this drying operation, the moisture of the tufts escapes through the front openings of the spaces 15.

Then, the bolts 21 are unscrewed, the mould is opened by the removal of its upper part, and the brushes are taken out. Thereafter, the bent bristle brushes retain the tuft shape 29 permanently. The device is immediately ready for renewed use.

The strips 1, 5 and 14 and the blocks 13 are made of suitable non-metallic material which does not scorch the bristles under the influence of heat. For example these moulding parts may be made of suitable plastics. The remaining parts of the device are made of stronger, preferably metallic non-corrosive material, for example, of an aluminum alloy. These metallic parts re-inforce the non-metallic parts so that the mould will not be distorted by heat.

The device makes it unnecessary to touch or to handle the brushes directly during the boiling and drying treatment, and makes it possible to place a large quantity of brushes into the boiling bath and into the drying chamber by less work than the handling of the individual brushes would require.

We desire it understood that our invention is not confined to the particular embodiment shown and described, the same being merely illustrative, and that our invention may be carried out in other ways without departing from the spirit of our invention as it is obvious that the particular embodiment shown and described is only one of the many that may be employed to attain the objects of our invention.

Having described the nature of our invention, what we claim and desire to protect by Letters Patent is:

1. A device for making bent bristle brushes comprising a base, a two part mold carried by said base, the two mold parts being formed to define when united in mold-

ing association a cavity unobstructedly open at one end and having a rounded curvature opposite from said opening, for receiving the forward portion of a tuft of assembled bristles through said open end to be forced against said curvature with the rear portions of the bristles protruding from said open end, said cavity having dimensions substantially coinciding with said forward portion of the assembled bristles and said open end being shaped to substantially conform to the cross section of the protruding portion of said tuft of assembled bristles, means carried by said base and spaced from said open end for supporting the tuft of assembled bristles when inserted in said cavity against displacement by the resiliency of the bristles forced against said curvature and means adjacent the forward end of the lower of said two mold parts for retaining said protruding portion of said assembled bristles against sagging.

2. A device as set forth in claim 1 wherein said tuft supporting means is positioned in front of and opposite said open end.

3. A device for making bent bristle brushes comprising a base, a bristle shaping portion carried by said base and having a male and a female interfitting parts, said male part substantially coinciding in cross section with said female part for insertion therein, said female part being formed to thereby define a cavity extending transversely to the line of insertion unobstructedly open at one end and having a rounded curvature opposite from said open end, for receiving the forward portion of a tuft of assembled bristles through said open end to be forced against said curvature with the rear portion of said bristles protruding from said open end, said cavity having dimensions substantially coinciding with said forward portion of the tuft of assembled bristles and said open end being shaped to substantially conform to the cross section of the protruding portion of said tuft of assembled bristles, means adjacent the open end of the cavity and in substantial alignment with the bottom wall of said cavity for retaining said protruding portion of said bristles against sagging, and means carried by said base and spaced from said cavity opposite said open end for supporting the assembly of bristles against displacement when inserted in said cavity.

4. A device for making bent bristle brushes by wet state soaking of the bristle assembly while holding the bristles shaped to the bent condition comprising a base, a mold carried by said base, the mold having a cavity unobstructedly open at one end and having an arcuate wall opposite from said opening for receiving the forward portion of a tuft of assembled bristles through said open end, yieldably to be forced against said arcuate portion to guide the said bristles of the tuft at the forward end toward each other, and with the body portion of the bristles protruding slidably from said open end, said cavity at its side walls having dimensions substantially coinciding with said forward portion of the assembled bristles and said open end being shaped substantially to conform to the cross-section of the protruding body portion of said tuft of assembled bristles for slidably receiving the same therethrough and leave an opening through which fluid may enter said mold cavity, means spaced from said open end for supporting the body portion of the tuft of assembled bristles, when inserted in said mold cavity, to hold the assembled bristles against displacement by the resiliency of the bristles forced against said arcuate wall, while leaving the cavity open as described and a second support means located substantially in alignment with the bottom of the cavity for retaining the body portion of the tuft of assembled bristles against sagging.
